Attorney.

UNITED STATES PATENT OFFICE.

ALBERT ROY GIRTON, OF BLOOMSBURG, PENNSYLVANIA, ASSIGNOR TO AMERICAN CAR AND FOUNDRY COMPANY, OF NEW YORK, N. Y., A CORPORATION OF NEW JERSEY.

SPRING-OILER.

1,354,903.

Specification of Letters Patent.

Patented Oct. 5, 1920.

Application filed June 25, 1918. Serial No. 241,814.

To all whom it may concern:

Be it known that I, ALBERT ROY GIRTON, residing a Bloomsburg, Columbia county, State of Pennsylvania, and being a citizen 5 of the United States, have invented certain new and useful Improvements in Spring-Oilers, of which the following is a full, clear, and exact description, such as will enable others skilled in the art to which it applies 10 pertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a vertical sectional view of a wheel and bearing showing the device in elevation;

Fig. 2 is a side elevation;

25 Fig. 3 is a longitudinal sectional view;

Fig. 4 is an end elevation looking at the ingress port;

Fig. 5 is an end elevation looking at the opposite end or egress port; and

30 Fig. 6 is a longitudinal sectional view before bending the fingers or assembling the spring and valve.

The purpose of the invention is to provide a lubricating device of simple construction, 35 wherein use is made of cheap and easily manufactured parts capable of ready assembly with a minimum expenditure of labor, and one that will have, substantially, a clear and unobstructed passage therethrough at 40 predetermined times.

To provide for such simple construction and assembly, it is proposed to make the casing hollow and of ductile material and to form slots that extend longitudinally from 45 one end through the major portion of the length of the casing and thus produce bendable extensions or fingers between the slots.

The passage through the casing is provided with a constricted portion having a 50 valve seat formed on one side and the opposite side is flared or curved to form a lubricant ingress port. To close and control the port, an approximately disk-like valve, hav-

ing convex and concave faces or sides is employed.

55

To maintain the valve in its operative position, a spring is used which has one of its ends seated in the concavity of the valve, and when the extensions or fingers are bent inwardly toward each other until they are 60 in contact, the slots have their open ends closed and a seat is formed by the inner wall of the converging fingers for the other end of the spring. Thus the valve and spring are retained within the casing. One 65 end of the casing is provided with a tool-engaging portion and also with a section adapting the oiler to be removably secured in position, as, for example, in a car wheel.

In the embodiment shown, the casing A 70 may be formed of any suitable material, which is preferably ductile, so that the various operations of manufacture and assembly will result in its being properly made. This casing is hollow and the passage therethrough is of different diameters 75 due to the convergence of the walls extending inwardly from the valve seat.

As shown in Fig. 3, at the right hand side, the passage terminates in an ingress port 80 10 that is provided with an outwardly flaring or curving wall 11. This produces a configuration that is similar to the mouth of a bell and facilitates the entrance of a nozzle of a grease gun. The inner end of the 85 flared portion has an opening 12 that constitutes the inner end of the port 10.

The inner wall of the passage on the opposite side this opening 12 also flares or curves outwardly, and is preferably so 90 formed that a hemispherical valve seat 13 is produced. From adjacent the valve seat 13, inwardly, the wall of the casing is relatively thin, and beginning at a point near where the largest diameter of the valve seat merges 95 into the wall of the casing, open-ended slots 14, 15, 16 and 17 are formed. These slots extend longitudinally through the major portion of the length of the casing A to within a short distance from the valve B 100 and are spaced circumferentially.

Between each of the slots 14, 15, 16 and 17 sufficient material is left to form fingers or extensions 18, 19, 20 and 21. As these fingers or extensions are parts of a circle 105 they are therefore segmental or arcuate. As

the casing A is preferably of malleable iron, the fingers 18, 19, 20 and 21 may be bent without injury to its fibers.

To coöperate with the valve seat 13, a 5 disk-like valve B is employed. In the embodiment shown, this valve has a convex face 22 that is adapted to closely conform to the valve seat 13, while its opposite face is provided with a concavity or depression 23 which serves as a spring seat. The valve 10 also has a cylindrical portion 24. The preferred shape of the valve B is shown in Fig. 3, and is generally concavo-convex.

In order that the valve B may be normally maintained on its seat 13 for closing 15 the opening 12 and controlling the ingress port 10, a spring 25 is used. This spring may be of any variety of the helical type and is so formed that one end will seat in 20 the concavity 23 or press against the valve B.

To maintain the spring 25 in position within the casing A, the fingers or extensions 18, 19, 20 and 21 have their free ends bent inward toward each other. This bending 25 is continued until the sides of the slots adjacent their open ends are in contact, as shown in Figs. 1, 2, 3 and 5, thus closing the slots. These slots, when closed, have an ogival shape, or in other words, their longitudinal sides converge. At the same time, 30 the free ends being arcuate in shape form an approximately round opening C at the end of the casing which serves as a lubricant egress port. The slots will also serve 35 as lubricant egress ports so that whatever lubricant enters the ingress port 10 will freely pass to the bearing or into the reservoir provided.

Externally, at one end of the casing A, 40 there is formed a hexagonal tool-engaging portion D. The casing is also provided with the screw threads E so that the device may be interlocked with a bearing, the threads adapting the device to be removably 45 secured in an operative position.

It will be noticed that the fingers 18, 19, 50 20 and 21 form a tapered portion extending from the threads E. The tapering of the inner wall of the fingers provides a means 55 for retaining the spring in position, as one end of the spring bears against said wall near the inner end of the casing.

To assemble the device, the valve and its 60 spring are inserted into the casing, the open or inner end is set on a suitable concave seat and the fingers 18 to 21 are caused to converge by a suitable blow on the outer end D thereby locking all the parts in assembled relation.

Various diameters of wire may be used in 65 forming the spring in conformity with the type of lubricant employed.

From the above description of the lubricating device, it will be seen that it embodies 70 a very simple construction and one

of its advantages lies in the fact that the interior of the casing is substantially clear and free of obstructions, such as a valve stem. This permits the casing to receive a larger quantity of lubricant than is usual, 75 and with the elimination of space occupying members, allows the lubricant to freely pass to the bearing without oozing outward past the valve and through the ingress port 10.

It will be observed that the casing is slotted longitudinally from its inner end almost to the valve seat at its outer end and a slight movement of the valve inwardly 80 will permit ingress of lubricant, which may be fluid oil or heavy grease, and immediately such lubricant will find uninterrupted egress passage through the longitudinal slots.

What I claim is:

1. A lubricating device, which comprises a casing having a valve seat near one end, and its body portion provided with longitudinally extending slots, the free ends of the material therebetween being brought 90 into contact to form an egress port at one end of the casing.

2. A lubricating device, which comprises a casing having a valve seat formed therein near one end, and its body portion provided with longitudinally extending slots, the free ends of the material therebetween being bent 95 inwardly thereby closing the slots and forming interiorly a seat for a spring, a disk-like valve adapted to engage with the valve 100 seat, and a spring interposed between the valve and the spring seat to normally maintain the valve seated.

3. As a new article of manufacture, a lubricating device comprising a hollow casing having a wall of varying thickness to form a valve seat, one end of said casing being provided with slots that extend longitudinally inward, the extensions formed therebetween being bent inwardly until the 110 sides adjacent their free ends contact with each other and close the open ends of the slots and also to form a spring seat, a valve to engage with the valve seat, and a spring having its ends, respectively, engaging with 115 the valve and the spring seat.

4. A lubricating device, which comprises a hollow casing slotted longitudinally for the greater part of its length, the material lying between the slots being bent inwardly 120 toward each other until the sides thereof adjacent the free ends are in contact and produce ogival-shaped closed slots.

5. A lubricating device, which comprises a hollow casing having a bell-mouth opening at one end, a valve seat formed around one end of the opening, the remaining length of wall being slotted and converging, a concavo-convex disk-like valve to engage 125 with the valve seat, and a spring having 130

one of its ends seated in the valve and its other engaging with the inner surface of the converging wall.

6. A casing for an oiler, which comprises 5 a hollow member having one of its ends slotted to provide fingers, the fingers adjacent their free ends being brought into contact engagement to form an approximately round lubricant opening and at 10 the same time to close the open ends of the slots.

7. A lubricating device, which comprises a casing provided with a longitudinal passage, said passage having a constricted portion 15 with a valve seat formed on one side, a disk-like valve to engage with said seat and close the passage, said casing being also provided with longitudinal extending slots forming lubricant exits and with a clear 20 opening for the inner end of the passage, and a spring having one of its ends engaging with the wall of the passage and its opposite end engaging with the valve.

8. A lubricating device, which comprises 25 an approximately tubular casing provided longitudinally with slots forming spaced fingers of the material lying therebetween, said fingers being capable of being bent until the sides thereof adjacent their free ends 30 contact with adjoining fingers, thus closing one end of each of the slots and at the same time forming a lubricant exit port at the end of the casing, the inner wall of the casing being provided with a flange having an 35 opening therein of lesser diameter than the passage, a valve seat formed on the inner face of the flange and concentric to the opening, the other face of the flange flaring outwardly, a disk-like valve having con- 40 cavo-convex faces, and a helical spring having one end seated in the concavity of the valve and its opposite end bearing against the inner wall of the casing passage near the lubricant exit port at the end thereof.

45 9. A casing for a lubricant device which comprises a tubular member having an ingress port at one end, a plurality of spaced open-ended slots extending longitudinally

inward from the other end of the casing, the spaced fingers formed therebetween being 50 adapted to be brought together to close the slots and at the same time form an egress port at one end of the casing, a tool-engaging portion concentric with the ingress port, a valve seat formed intermediate the ports, 55 and means serving to removably secure the casing in position.

10. A lubricating device, which comprises a hollow casing having circumferentially spaced slots extending inwardly 60 from one end, and forming bendable fingers therebetween said fingers being bent inward until the corners of their free ends have contact with adjoining fingers, thereby closing the outer ends of the slots and causing 65 their side walls to converge, a valve seat formed intermediate the ends of the casing, an ingress port adjacent the valve seat, a valve having a convex face to engage the seat and a concavity on its opposite face 70 for receiving the end of a spring, and a spring having one of its ends seating in the casing adjacent the ends of the slots and serving to normally maintain the valve on its seat and the ingress port closed. 75

11. A lubricating device, which comprises a tapering slotted casing including a valve seat, a disk-like valve and a spring.

12. A lubricating device, which comprises a hollow casing having a tapered lubricant 80 egress portion serving as a spring seat, a valve seat in the casing, a valve and a spring.

13. A lubricating device, which comprises a hollow, tapering and slotted casing serving 85 as a spring seat including a valve seat, a valve and a spring.

14. A lubricating device which comprises a hollow casing, slotted longitudinally from one end, the slots permitting a portion 90 of the casing to have a taper, a valve seat in the casing, a valve, and spring inclosed and retained by the tapered portion.

In witness whereof I have hereunto set my hand.

ALBERT ROY GIRTON.
